UNITED STATES PATENT OFFICE.

HARRY D. CARTER, OF HARRISBURG, ILLINOIS.

MEASURING DEVICE.

Application filed July 3, 1924. Serial No. 724,074.

This invention relates to improvements in measuring devices, more particularly to devices of this character associated with counters or the like on which goods are displayed for sale, and has for one of its objects to 5 simplify and improve the construction and increase the efficiency and utility of devices of this character.

Another object of the invention is to provide a device of this character, comprising 10 a metal plate having transverse graduations and with perforations through certain uniformly spaced graduations to receive fastening devices whereby the plate is attached 15 to a support, preferably of the same width as the plate, the outer ends of the fastening devices increasing the visibility of the graduations through which they extend.

With these and other objects in view, the 20 invention consists in certain novel features of construction as hereinafter shown and described and then specifically pointed out in the claims, and in the drawings illustrative of the preferred embodiment of the invention—

Fig. 1 is a perspective view of a conventional sales counter with the improved measuring device attached.

Fig. 2 is plan view, enlarged, of a portion 30 of the improved device.

Fig. 3 is a sectional detail.

The improved device comprises a metal strip represented at 10, and generally a trifle over thirty six inches or one yard in length 35 and about five eighths of an inch, more or less, in width, to correspond to the thickness of what are known as counter stops, usually employed in certain classes of retail stores, and represented at 11, the floor or top 40 of the counter being indicated at 12.

The strip 10 is preferably rounded at the ends, to obviate sharp corners which would be liable to catch on the clothing of clerks or others.

The graduations, indicated at 13, may be 45 sunken in the upper surface of the plate, as indicated in Fig. 3, or otherwise arranged, as may be preferred. The graduations may be disposed at any desired distance apart, 50 but will generally be in yards and fractions of yards, or inches, as shown in Fig. 2, but other graduations may be employed.

At certain distances the plate 10 is apertured to receive attaching devices 14, for instance screws with flat heads flush with the 55 upper face of the plate as shown in Fig. 3. When the graduations are in yards and fractions of yards the apertures will generally be formed through quarter yard graduations, or at every nine inches, and the enlarged heads of the attaching devices will 60 thus serve to assist the clerk in making the measurements by increasing the visibility of the graduations.

Generally the plate 10 will be of aluminum 65 or the like while the attaching devices 14 will be of brass or some color other than that of the plate, to increase the visibility, and thus correspondingly increase the efficiency of the device.

The plate 10 being of metal will not be worn or fractured by goods being drawn over it or otherwise brought in contact therewith.

The improved device is simple in construction, can be readily applied, and will be found of especial advantage for use in stores wherein counter devices are employed with the margins elevated as shown in Fig. 1 to prevent the displacement of the goods.

Being thus located on the upper edges of the counter stops the graduated plates will never be obscured by the goods being displayed.

The preferred embodiment of the invention is disclosed in the drawings and set forth in the specification, but it will be understood that modifications within the scope of the claimed invention may be made in the construction without departing from the 90 principle of the invention or sacrificing any of its advantages.

What I claim is:

A counter comprising a top, a stop abutting one side edge of and extending above 95 said top and formed with a flat upper face, a graduated strip extending lengthwise of and mounted directly upon said upper face, said strip having its side edges flush with the side edges of the stop and further having each end rounded to obviate sharp corners, said strip further formed with equi-distant spaced countersunk openings, each intersected diametrically by the plane of a gradu-

tion extending transversely of the strip, said openings further intersected diametrically by the plane of the longitudinal median of the strip, and headed securing elements extending through said openings and engaging with the stop for fixedly securing the strip to the stop, the heads of said devices counter-sunk in said openings, flush with the upper face of the strip and providing indications for certain measurements. 10

In testimony wherof, I affix my signature hereto.

HARRY D. CARTER.
